Hoffman et al., "Electrical Connector Housing", U.S. Appl. No. 29/360,150, filed Apr. 21, 2010.

Primary Examiner — Daniel Bui

(74) *Attorney, Agent, or Firm* — Keating & Bennett, LLP

(57) **CLAIM**

The ornamental design for an electrical connector housing, as shown and described.

DESCRIPTION

FIG. 1 is a perspective view of an electrical connector housing according to our new design;

FIG. 2 is a top view thereof;

FIG. 3 is a front view thereof;

FIG. 4 is a left view thereof;

FIG. 5 is a back view thereof;

FIG. 6 is a right view thereof; and,

FIG. 7 is a bottom view thereof.

The broken line in the drawing views is included to show unclaimed subject matter only and forms no part of the claimed design.
